UNITED STATES PATENT OFFICE

RALPH D. WYCKOFF, OF PITTSBURGH, PENNSYLVANIA, ASSIGNEE TO GULF PRODUCTION COMPANY, OF HOUSTON, TEXAS, A CORPORATION OF TEXAS

AUTOMATIC DRILLING CONTROL

Application filed August 25, 1930. Serial No. 477,727.

My invention relates to an automatic drilling control and has to do, more particularly, with the control of rotary drilling equipment for oil wells and the like.

5 The primary object of my invention is to provide, in a rotary drilling apparatus, novel means for automatically regulating the feed pressure of the drilling bit by controlling the drill stem weight suspended by the draw works.

10 It is a further object of my invention to provide, in a rotary drilling apparatus, means for automatically maintaining the drill bit at constant feed pressure, in spite of considerable variation in the torque demand upon the rotating means, yet which will, upon an excessive torque demand, effect a decrease in the feed pressure, and partial retrieval of the bit as well, if such excessive torque demand be of prolonged duration.

15 It is a further object of my invention to provide an automatic control device for rotary drilling apparatus which is selective and may be set to regulate the bit feed pressure in accordance with either the torque demand upon the stem rotating means, the suspended 20 drill stem weight, or both.

25 A further object of my invention is to provide an efficient, comparatively simple, inexpensive, and light weight apparatus for accomplishing the above objects, which may be readily installed for use with existing conventional drilling equipment with a minimum of modification thereof.

30 Further objects, and objects relating to details and economies of construction and operation, will definitely appear from the detailed description to follow. In one instance, I accomplish the objects of my invention by the devices and means described in the following specification. My invention is clearly defined and pointed out in the appended claims. A structure constituting a preferred embodiment of my invention is illustrated in the accompanying drawings, forming a part of 35 this specification, in which:

Figure 1 is an elevational view of conventional rotary drilling equipment as set up for control by apparatus embodying my invention;

Fig. 2 is a plan view of a preferred form of my automatic controlling apparatus for use with the drilling equipment shown in Fig. 1, the hoist power unit in this instance being an electric motor independent of the power unit used for turning the drill stem;

Fig. 3 is a plan view of a slightly modified form of my invention in which the hoist power is derived from the main power unit which turns the drill stem,

Fig. 4 is a view of a preferred form of weight indicator element adapted for use with apparatus constituting a preferred embodiment of my invention, a portion of the housing of which is broken away to disclose 55 the internal construction;

Fig. 5 is a diagram of the weight indicator element and the Wheatstone bridge and contact making galvanometer to be used therewith;

Fig. 6 is a cross sectional view of a torque indicator element adapted for use with the preferred embodiment of my invention;

Fig. 7 is a detail view of the carbon pile telemeter portion of the indicator illustrated 75 in Fig. 6, showing the electrical connections;

Fig. 8 is a diagram of the torque indicator and the Wheatstone bridge and contact making galvanometer to be used therewith; and

Fig. 9 is a plan view of the torque indicator element assembled with the rotary table 80 of the drilling equipment.

Like reference numerals denote like parts throughout the several views.

It is a well known fact that an oil well may 85 be drilled more satisfactorily when the weight on the bit and the torque applied to the bit are held within certain limits, dependent upon the type and condition of the formation being drilled. Such control is, in 90 general, conducive to less breakage of drilling equipment, faster drilling, and straighter holes. The production of straighter holes is of particular importance both in economy of drilling and in subsequent operation of the 95 well. For this reason, automatic apparatus has been designed to take the place of the usual manual control. The automatic systems now in use comprise, essentially, a differential drive between the drill stem rotat- 100

ing member and the draw works, so arranged that an increase in the torque demand upon the rotating member effects, or tends to effect, lifting of the drill stem, thus maintaining an inverse proportion of total torque demand and feed pressure upon the bit. In this connection, it should be pointed out that the feed pressure of the bit against the formation being drilled is due to, and directly proportional to, that portion of the total drill stem weight not suspended by the draw works; and that decreasing the suspended weight increases the bit pressure accordingly. Conventional draw works consist of a swivel attached to the upper end of the drill stem permitting rotation of the stem without interference from the falls and tackle supporting the stem through the swivel. One free line of the tackle, known as the "deadline", is anchored, the other free line being windable upon the hoisting drum which effects lifting and lowering of the drill stem and thus controls the suspended weight and feed pressure as above explained.

There are, however, certain conditions commonly encountered in drilling in which the total torque applied at the top of the drill stem does not represent the torque on the bit itself. Thus, friction of the drill stem on the side of the bore hole does not represent torque on the bit, and the driller may wish to eliminate the torque control under such conditions, but retain the weight control. Further, under other conditions, control in accordance with indicated torque alone is the most satisfactory. With the existing automatic equipment such selection is impossible, since only the ratio of weight to torque may be changed, it, therefore, being necessary to resort to manual operation if control in accordance with either factor, singly, is desired.

In general, my invention consists in employing suitable weight and torque responsive devices, which, for lack of a better term, I shall designate as "indicators", these being so connected to the drilling equipment, either by electrical or mechanical means, as to control the feeding pressure of the bit against the formation being drilled. This may be accomplished through the medium of a slow speed driving mechanism coupled to the main hoist drum, or to a special drum to which the "dead line" is attached, or by other means effecting variation in the suspended drill stem weight. In the preferred embodiment of my invention, a slow speed hoist drum is substituted for the usual dead line anchor, and is rotated by a reversible electric motor driving through a worm reduction gearing. This type of reduction gearing is irreversible, that is, may be turned only by the motor, thus preventing rotation of the drum and motor due to the strain imposed by the tensioned line. Control apparatus for the

motor comprises a reversing switch having an intermediate "off" position, a selective relay for actuating said switch, and suitable weight and torque indicators electrically connected to said relays. For the purpose of permitting selection of the most desirable factor for control, that is, torque, or weight, or a combination of both, a selector switch is provided intermediate the indicators and the relays.

Referring to the numbered parts of the drawings in which I have shown a preferred embodiment of my invention, the drill stem 10, having a bit 11, is supported at its upper end by the swivel 12, which in turn is supported by the usual falls and tackle broadly designated as 13. One free end of the tackle is wound upon the main hoist drum 14, while the other, commonly known as the "dead line", is anchored to and wound upon a slow speed drum 15. A conventional rotary table 16 is employed for rotating the drill stem and an indicating device 18 for indicating the torque demand is applied thereto. This indicator may be of any suitable type, mechanical or electrical, and, if an electric motor be employed for driving the table, a wattmeter in the power circuit thereof will serve the purpose. A weight indicator 17 of any suitable type is provided for indicating the suspended drill stem weight, and is preferably installed below the falls and tackle 13 to eliminate errors and necessary computations due to the varying length and weight of the tackle during the feeding of one length of drill stem.

Referring to Fig. 2 which shows, diagrammatically, a preferred form of controlling apparatus, there is provided a reversible electric motor 19, driving the hoist 15 through a reduction gearing 20, which is preferably of the irreversible worm type and, therefore, serves the additional function of a drum check, preventing unreeling of the line due to strain imposed thereon by the suspended drill stem weight. A switch is provided for controlling the motor and is preferably of the type having a normally balanced switch arm 21 bearing contacts 1, 2, and 3 to which are connected the several leads of the motor power supply (not shown). The leads from the motor terminals 23, 24 and 25 are branched and are connected to two oppositely disposed and reversely arranged sets of contacts 23^a, 24^a, 25^a, and 24^b, 23^b, 25^b, the former set when engaged by switch arm contacts 1, 2, 3, respectively, causing operation of the motor in a direction to effect unreeling of the hoist line, the latter set, when engaged by switch arm contacts 1, 2, and 3, causing the motor to turn in the reverse direction to effect reeling of the line. For thus selectively actuating the switch arm 21 by means of an electric current, a pair of solenoids 26 and 27 are provided having terminals 28 and 29 and a common terminal 30. The switch arm is central-

ly mounted upon a rockable member 31 which in turn is balanced upon the fulcrum 32. From each end of the rockable member 31 cores 33 and 34 depend into the ends of the solenoids 26 and 27, respectively. It will be seen that energization of solenoid 26 will attract core 33 and rock the switch arm 21 from "off" position until contacts 1, 2 and 3 engage contacts 23^a, 24^a and 25^a. Conversely, the energization of solenoid 27 will attract core 34 and move the switch arm in the opposite direction causing engagement of contacts 1, 2 and 3 with contacts 24^b, 23^b and 25^b. The switch is of such construction that it automatically returns to its intermediate or "off" position upon de-energization of solenoids 26 and 27.

The weight and torque indicators 17 and 18 are provided with contacts, and indication of unsatisfactory conditions are set up by the closing of respective electrical circuits thereby. The indicators are so constructed as to be readily adjustable, as for example by resetting the contacts thereof in accordance with the size and type of drill bit employed, the strength of the drill stem, the formation being drilled, and the total drill stem weight. In the arrangement shown in Fig. 1, a new setting of the weight indicator is necessary each time a length of drill stem is added, since the indication is of suspended drill stem weight, and the effective weight on the bit is that portion of the total drill stem weight not suspended by the draw works. In Figs. 4 and 5 there is disclosed what I deem to be a preferred form of weight indicator which is particularly well adapted for use as a part of my control apparatus. The indicator element 17^x comprises a tension link 17^a having shoulders 17^b, a carbon pile telemeter element 17^c of the type disclosed in U. S. Patent, No. 1, 528,627, and a housing 17^d enclosing the reduced portion of the link 17^a and the telemeter 17^c, and having collars 17^e which prevent separation of the parts of the link 17^a in the event of rupture of the reduced portion of the link 17^a. The telemeter 17^c of indicator element 17^x is in series with the variable resistance 17^r and battery 17^s and is connected to the terminals of a Wheatstone bridge 17^y which in turn is connected to the contact making galvanometer 17^z which makes connection of terminal 35 with terminal 38 in the event of a condition of inadequate bit feeding pressure, and connection with terminal 39 in the event of a condition of excessive bit feeding pressure. In Figs. 6 to 9 there is disclosed what I regard to be a preferred form of torque indicator element 18^x especially well adapted for use as a part of my control apparatus. It comprises a tension bar 18^a similar to the tension bar 17^a of my weight indicator, a carbon pile telemeter 18^b, a bearing block 18^c adapted for disposition about the pinion shaft 16^a

of the rotary table 16, and a housing 18^d within which the bar 18^a, telemeter 18^b, and block 18^c are housed. The block 18^c, under variations in torque stress moves slightly longitudinally in the housing 18^d due to changing thrust of the pinion 16^b against the ring gear 16^c of the rotary table and the tension of the chain 16^d. Bar 18^a is accordingly elongated and shortened, which variations in length are transmitted by telemeter 18^b as variations in current from battery 18^s. Variable resistance 18^r, battery 18^s, and telemeter 18^b are in series and are connected to the Wheatstone bridge 18^w which in turn is connected to the contact making galvanometer 18^z, as shown in Fig. 8. Galvanometer 18^z connects terminal 36 with terminal 40 in the event of a condition of excessive torque of a condition of low torque. Terminal 35 of the weight indicator and terminal 36 of the torque indicator are jointly connected to one terminal of the battery 37. Should there occur a condition of excessive torque demand, insufficient torque demand, excessive weight upon the drill bit, or inadequate weight upon the drill bit, indicator terminals 40, 41, 39, or 38, respectively, would be electrically connected with said battery terminal by the indicating device involved, through terminal 35 or 36.

Due to the limited size of the contact elements in most sensitive circuit closing indicators, the power carried by the primary indicating circuits is, of necessity, too low for direct actuation of the switch arm 21, and must be translated. For this purpose, in the embodiment illustrated, I employ a selective relay mechanism having relays 46, 47, 48 and 49, the terminals 42, 43, 44, and 45 of which are respectively connected to the terminals 38, 39, 40, and 41 of the indicators. Torque responsive relays 48 and 49 are provided with a common lead connected to one end of an auxiliary coil 50, the other end of which is connected to terminal 51. Weight responsive relays 46 and 47 are provided with a common lead connected to terminal 52. Terminals 51 and 52 are jointly connected to the opposite side of battery 37 from terminals 35 and 36, thus completing the several indicating circuits through the indicators. A relay arm 53 is mounted intermediate the relays 46, 47, 48 and 49, and has, pivotally attached thereto, a core portion 54 subject to attraction by the auxiliary coil 50 whenever, and as long as, there exists an unsatisfactory indicated torque condition. Springs 55 are provided for maintaining the arm 53 in normal central position when not drawn toward coil 50. Contactors 56 and 59, movable by the relays 46 and 49, respectively, are connected to a common terminal 60. Contactors 57 and 58, movable by relays 47 and 48, respectively, are connected to a common terminal 61. Contactors 56, 57, 58, or 59 are

movable into engagement with contacts 62 on the relay arm 53 in accordance with conditions of inadequate weight upon the drill bit, excessive weight upon the drill bit, excessive torque demand or insufficient torque demand, respectively.

A source of control power (not shown) is connected to terminal 63 of the relay arm and terminal 30 of the switch operating solenoids, 10 thus completing the switch actuating circuits through the relays. When torque sensitive relays 48 or 49 are energized, coil 50, being in series therewith, draws relay arm 53 away from weight responsive contactors 56 and 15 57. Contactor 56 or 57, though projected by its weight responsive relay 46 or 47, is arrested in its extent of movement by stop 66 or 67 and can not engage contacts 62 when arm 53 is under attraction 20 by coil 50. In this manner, should torque and weight conditions be out of harmony, that is, should there simultaneously occur a condition of excessive torque demand when the drill stem weight on the bit is sub- 25 normal, or should the torque demand be low though the weight upon the bit is above normal, the torque indication would be given the control in preference to the weight indication.

20 For the purpose of permitting selection of either the torque indication or the weight indication as the sole control factor; or for the purpose of temporarily disconnecting the automatic control in favor of the usual 25 manual control, a selector 68 is provided. This device is essentially a multiple switch connected in the conductors connecting the relay terminals 42, 43, 44, and 45 with the indicator terminals 38, 39, 40, and 41, and in 30 the conductor connecting one terminal of the battery 37 with the indicator terminals 35 and 36. By adjustment of the selector arm to one or the other of its several settings, the continuity of any one or several of the indicating 35 circuits may be interrupted, thus selecting, for purposes of control, those indications the circuits of which are unbroken. If it be desired to temporarily employ manual control, the battery 37 may be disconnected from 40 the indicators by the selector, thus eliminating the automatic control as an entirety.

A further refinement consists in the provision of a speed control 69 for the motor, whereby the winding rate of the drum 15 may 45 be controlled and smoother action be provided. It is also desirable to provide the drum 15 with a brake 70 whereby anchorage of the line may be effected. This is of advantage, particularly, when a change speed 50 gearing is employed with the worm gearing 20 for more rapidly raising the traveling blocks of the falls-13 when adding a new length of drill stem.

In the event that the indicating devices 55 are sensitive to normal rapid fluctuations, a

time-lag device or devices should be provided either in the indicators, the relays or some other portion of the control circuit for preventing any but variations of reasonably long duration from operating the hoist equipment. 70

With the selector 68 set for control in accordance with either the torque indication or the weight indication, singly, the operation of the control apparatus should be obvious. The selected indicator having been adjusted 75 to limits in accordance with safe and efficient stresses, when a condition in excess of, or below, the set value occurs, the proper indicating circuit is closed, the respective relay is energized, the respective control circuit 80 is closed by the relay contact moved, the motor switch is closed in accordance with the indication, and the drum 15 is turned to reel or unreel the line suspending a portion of the drill stem weight, thus decreasing or increasing the feed pressure upon the bit and bringing the conditions back to normal. When the normal operating condition is reached, the closed indicating circuit is 85 opened by the indicator, the control circuit is opened by the relay, the switch arm 21 returns to normal "off" position, the hoist drum 15 is stopped, and the line is automatically anchored by the drum and its irreversible worm gearing 20. 90

With the selector set for control in accordance with indications both of torque and of suspended weight, the operation is similar, being subject to indications in excess of, or below, the predetermined settings of either 100 indicator. However, it sometimes happens that the indications of torque demand and suspended drill stem weight are not in harmony, both being greater than, or both less than, the normal safe and efficient set values. 105 It is for proper operation under such abnormal conditions that the auxiliary coil 50 is provided in the torque indicating circuits. As long as a condition of unsatisfactory torque demand, high or low, exists, the relay 110 arm 53 will be drawn to a position out of possible contact by weight responsive contactors, 56 and 57, thus automatically eliminating the weight indication, temporarily, as a control factor. Such operation permits settings of 115 the torque indicator contacts such that when excessive torque is required, the drill stem is slightly lifted or retrieved, lessening the feed pressure on the bit, and further, when the torque demand becomes too low, the drill stem 120 is slightly lowered, increasing the feed pressure on the bit. It is also contemplated, in this connection, to place auxiliary contacts on the relay arm 53, whereby circuits operating 125 warning or signal devices may be closed, thus calling the operator's attention to the existence of the abnormal conditions.

In Fig. 3, I have disclosed a slightly modified embodiment of my invention which is particularly adapted for use in oil fields in 130

which polyphase electric current is not available for driving the hoist. This form of my invention employs a special reversing clutch having a bevel gear 71 driven from a shaft 72

5 which is connected to the main power unit (not shown) of the well drilling equipment. A shaft 73 for coupling to a worm gearing such as that shown at 20 of Fig. 2 has freely mounted thereon a pair of opposed bevel gears 74 and 75 which are engaged at opposite sides with the gear 71 and, therefore, rotate upon the shaft 73 in opposite directions. Attached to and housed between said gears 74 and 75, are provided a pair of spaced electromagnetic clutch elements 76 and 77 which rotate with their respective gears. In the space between the electromagnetic clutch elements 76 and 77 and keyed to shaft 73, but freely slidable axially thereon, is provided disk member 78 which is magnetically clutched by element 76 to cause rotation of shaft 73 in one direction, or by element 77 to cause rotation in the reverse direction. Should neither element 76 nor element 77 be energized, gears 74 and 75 rotate freely and no movement of shaft 73 takes place.

The windings of electromagnetic elements 76 and 77 are connected by any well known expedient, such as collector rings and brushes, to a set of terminals 79, 80, 81 and 82. Terminals 79 and 81 are connected to terminals 61 and 60, respectively, of the relays. Terminals 80 and 82 of the clutch windings are jointly connected to one lead from a source (not shown) of clutch operating current, the other lead therefrom being connected to terminal 63 of the relays, thus completing the clutch operating circuits through the relays. The relays, selector, and indicators 40 are identical, structurally, with those fully described in connection with the embodiment illustrated in Fig. 2 and need not be again described in connection with the clutch form of the invention illustrated in Fig. 3. When employing a clutch of this type, simple direct current may be employed for energization of its magnetic elements 74 and 75 and no switch such as shown in the embodiment illustrated at Fig. 2 is required, the clutch operation and direction being controlled directly by the contactors 56, 57, 58 and 59 of the relays.

Shaft 73 is coupled to a worm gearing and hoist such as shown at 20 and 15 of Fig. 2 and feed pressure upon the bit may thus be accurately controlled. Movement of relay contactors 56 or 59, responsive to conditions of low feed pressure and low torque respectively, connect the magnetic element 76 to the clutch operating power supply, cause disk 78 to engage gear 74 and rotate shaft 73 to increase the feed pressure upon the drill bit. Movement of relay contactors 57 or 58, responsive to conditions of high feed pressure and high torque demand respectively, connect the magnetic element 77 to the clutch oper-

ating power supply, cause disk 78 to engage gear 75 and rotate shaft 73 in the reverse direction to decrease the feed pressure upon the drill bit.

It will be observed that I have provided a selective control apparatus for regulating the feed pressure of a rotary drill bit in accordance with either the torque demand upon the drill stem, or the suspended drill stem weight, or both. My control apparatus is readily capable of adjustment to operate in accordance with safe and efficient values for different sizes and forms of drill stems and bits and for various earth formations.

My control apparatus may be set to maintain a substantially constant feed pressure upon the bit regardless of normal varying torque demands, yet in the event of an excessive torque demand, will give the torque indication exclusive control, causing reduction in feed pressure; or if such excessive demand be prolonged, effecting partial retrieval of the drill bit. Similarly, my control apparatus may be so set that a torque demand very far below that indicative of efficient drilling will automatically exclude the weight indication as a control factor and permit the feed pressure to be increased to the point where an efficient torque demand is effected.

I have provided a rotary drill control apparatus which is extremely sensitive and flexible and by which the drill bit can be maintained at values more closely approximating the optimum than heretofore possible either by manual or automatic devices.

Another feature of my invention is that the apparatus is light in weight, and may be easily transported to and installed in new locations. My apparatus employs no expensive high power, heavy-duty motors, heavy differentials, cumbersome and exposed chains, sprockets, and other parts requiring special mountings and accurate alinement. My apparatus is comparatively compact, the selector, relay and motor switch being capable of mounting in a single case, close to, or remote from, the indicators and the draw works. The motor for driving the slow speed hoist may be of low power, operating through a reduction worm gearing by direct drive, and the gear ratio may be readily changed to permit rapid lifting of the disconnected traveling blocks during addition of a new length of drill stem. If a special slow speed hoist drum be employed as disclosed, the main hoist drum is available for emergency use, which is a further advantage.

While the preferred embodiment disclosed employs an electric motor for driving the slow speed hoist, it is to be understood that my invention contemplates the substitution therefor of any suitable power device or of a reversing gear and clutch driven from the main power unit which drives the rotary table or other equipment. Such an adapta-

tion is necessary in fields in which electricity is not available as a source of power. Similarly, other means for reeling or tensioning the drill stem suspending line may be substituted for the slow speed hoist drum disclosed without departing from the spirit of my invention. The relay and switch constructions are also capable of constructional modification, the function of the parts disclosed being attainable by other equivalent constructions.

I am aware that, in several other particulars, the apparatus herein disclosed may be changed considerably without departing from the spirit of my invention. I, therefore, claim my invention broadly as indicated by the appended claims.

What I claim is:

1. A full-automatic well drilling apparatus comprising a drill stem, a bit thereon, means for rotating the drill stem, means for suspending a portion of the weight of the drill stem to decrease or increase the feeding pressure upon the bit, means sensitive to the instant torque upon the drill stem, which means effects operation of said suspending means to regulate the feeding pressure upon the bit in accordance with predetermined torque limits of safety and efficient drilling, and means effecting operation of said suspending means to maintain the feeding pressure at a substantially constant predetermined value, said last mentioned means being so associated for control of said suspending means as to be operative only when such operation is not in conflict with the operation of the suspending means by said torque sensitive means.

2. A full-automatic well drilling apparatus comprising a drill stem, a bit thereon, means for rotating the drill stem, means for suspending a portion of the weight of the drill stem to decrease or increase the bit feeding pressure against the formation being drilled, and means for controlling said drill stem weight suspending means to maintain a predetermined feeding pressure upon said bit so long as the torque set up in the drill stem is within safe limits, but causing instantaneous lifting of said drill stem in the event of an excessive torque demand regardless of the feeding pressure then existent upon the bit.

3. A full-automatic well drilling apparatus comprising a drill stem, a bit thereon, means for rotating the drill stem, means for suspending a portion of the weight of the drill stem to decrease or increase the bit feeding pressure against the formation being drilled, and means for controlling said drill stem weight suspending means to maintain a predetermined feeding pressure upon said bit so long as the torque set up in the drill stem is within safe limits, but causing instantaneous lifting of said drill stem in the event of an excessive torque demand regard-

less of the feeding pressure then existent upon the bit, said controlling means comprising weight sensitive control means, torque sensitive control means, and means for rendering said weight sensitive control means ineffective so long as an abnormal torque condition exists.

4. An automatic control apparatus for use with earth drilling equipment employing a drill stem and bit, means for rotating the drill stem, means for suspending a portion of the weight of the drill stem, and a power drive for said weight suspending means; power drive control means comprising an electric control circuit which when closed causes the power drive to increase the suspended drill stem weight, contactor means subject to actuation in accordance with instant factors of torque upon the stem rotating means and suspended drill stem weight, which contactor means normally control continuity of said electric control circuit in accordance with both of said instant factors to normally maintain the feeding pressure upon the bit and the torque upon the drill stem within predetermined safe and efficient limits, and means for eliminating the feeding pressure as a control factor when there exists simultaneously during the drilling, a conflicting condition of excessive torque and inadequate feeding pressure.

5. An automatic control apparatus for use with earth drilling equipment employing a drill stem and bit, means for rotating the drill stem, means for suspending a portion of the weight of the drill stem, and a power drive for said weight suspending means; power drive control means comprising an electric control circuit which when closed causes the power drive to increase the suspended drill stem weight, contactor means subject to actuation in accordance with instant factors of torque upon the stem rotating means and suspended drill stem weight, which contactor means normally control continuity of said electric control circuit in accordance with both of said instant factors to normally maintain the feeding pressure upon the bit and the torque upon the drill stem within predetermined safe and efficient limits, and means for eliminating the feeding pressure as a control factor when there exists simultaneously during the drilling, a conflicting condition of excessive torque and inadequate feeding pressure, or a conflicting condition of high feeding pressure and very low torque.

6. An automatic control apparatus for use with earth drilling equipment employing a drill stem and bit, means for rotating the drill stem, means for suspending a portion of the weight of the drill stem, and a reversible power drive for said weight suspending means; power drive control means comprising a circuit controlling operation of said

- reversible power drive, contactor means governing said circuit to effect an increase in the suspended drill stem weight upon the occurrence of a condition of excessive torque or 5 excessive feeding pressure in the drilling equipment and to effect a decrease in the suspended drill stem weight upon the occurrence of a condition of low torque or inadequate feeding pressure, and means for 10 eliminating feeding pressure as a control factor when there exists simultaneously during the drilling, a conflicting condition of excessive torque and inadequate feeding pressure.
- 15 7. An automatic control apparatus for use with earth drilling equipment employing a drill stem and bit, means for rotating the drill stem, means for suspending a portion of the weight of the drill stem, and a reversible power drive for said weight suspending means; power drive control means comprising a pair of electric control circuits, one of which when closed causes said power drive to increase the suspended drill stem weight, 20 the other of which when closed causes the power drive to decrease the suspended drill stem weight, contactor means rendered operative by a condition of excessive torque or excessive feeding pressure in the equipment 25 for closing the first mentioned of said control circuits, contactor means rendered operative by a condition of low torque or inadequate feeding pressure for closing the other of said control circuits, and means for 30 eliminating the feeding pressure as a control factor when there exists simultaneously during the drilling a conflicting condition of excessive torque and inadequate feeding pressure.
- 35 8. An automatic control apparatus for use with earth drilling equipment employing a drill stem and bit, means for rotating the drill stem, means for suspending a portion of the weight of the drill stem, and a reversible power drive for said weight suspending means; comprising a pair of electric control circuits, one of which when closed causes said power drive to increase the suspended drill stem weight, the other of which when 40 closed causes the power drive to decrease the suspended drill stem weight, contactor means rendered operative by a condition of excessive torque or excessive feeding pressure in the equipment for closing the first 45 mentioned of said control circuits, contactor means rendered operative by a condition of low torque or inadequate feeding pressure for closing the other of said control circuits, and means for eliminating the feeding pressure 50 as a control factor when there exists simultaneously during the drilling, a conflicting condition of excessive torque and inadequate feeding pressure, or a conflicting condition of high feeding pressure and very low torque.
- 55 9. An automatic control apparatus for use with earth drilling equipment employing a drill stem and bit, means for rotating the drill stem, and means for suspending a portion of the drill stem weight to regulate the bit feeding pressure, which comprises means sensitive to the weight suspended, means sensitive to the torque demand upon said stem rotating means, a reversible motor operating the weight suspending means, a switch for the motor, and selective relay means responsive to and energized by said weight and said torque sensitive means for actuating said switch in accordance with variations in torque demand and suspended weight, said relay having the characteristic of being preferentially responsive to variations in torque demand.
